CLAIM

The ornamental design for a massage hair brush as shown and described.

DESCRIPTION

FIG. 1 is a front, left and top perspective view of a massage hair brush, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged view of an area labeled 9 in FIG. 1.

The dash-dash broken lines shown in the drawings depict portions of the massage hair brush, and form no part of the claimed design. The dot-dash broken lines seen in FIGS. 1 and 9 depict enlarged view indicators, and form no part of the claimed design.
